UNITED STATES PATENT OFFICE.

WILLIAM DAVIS NAPIER, OF MOUNTAIN HOME, ARKANSAS, ASSIGNOR OF ONE-HALF TO THOMAS J. PERRY, OF SAME PLACE.

TONGUE-SUPPORT.

SPECIFICATION forming part of Letters Patent No. 394,932, dated December 18, 1888.

Application filed August 21, 1888. Serial No. 283,310. (No model.)

To all whom it may concern:

Be it known that I, WILLIAM DAVIS NAPIER, a citizen of the United States, residing at Mountain Home, in the county of Baxter 5 and State of Arkansas, have invented a new and useful Improvement in Tongue-Supporters, of which the following is a specification.

The object of my invention is to provide a simple, cheap, and durable tongue-supporter 10 so constructed and arranged as to accomplish the desired purpose without straining or unnecessarily wearing any of the parts of the vehicle; and it consists in a certain novel construction and arrangement of devices, fully 15 set forth hereinafter in connection with the accompanying drawings, and specifically pointed out in the appended claim.

In the drawings, Figure 1 is a perspective view of a wagon-bed with the improved 20 tongue-supporter applied thereto in the operative position. Fig. 2 is a detail view of the sliding plate, which is arranged on the bolster.

Referring by letter to the drawings, A designates the front bolster, B designates the 25 coupling or reach, and C the tongue, all constructed and arranged in the ordinary and well-known manner.

D represents a sliding plate, which is arranged 30 on the upper side of the bolster, and is held in place thereon by the king-bolt E, which passes through a longitudinal slot or opening, d, in the plate, and the front and rear ends of this plate are extended beyond the 35 respective sides of the bolster, and are turned down slightly and provided with apertures d' d'.

F represents a strong metallic coiled spring, and G G' represent wire loops, which extend 40 in opposite directions through the spring and terminate at their free ends in small hooks g g', which bear, respectively, against opposite ends of the spring, the closed ends of the loops projecting slightly beyond opposite ends 45 of the spring. The end of the loop G is connected by a suitable link, H, with the front end of the sliding plate, and to the loop G' is attached the rear end of the chain I, which is provided near its front end with a series of 50 depending or loose links or rings, K.

L designates a stationary plate, which is secured by means of screws or bolts l l to the tongue just in front of the whiffletree, and

the rear end of this plate is provided with an upturned hook, L', which is adapted to be engaged by one of the depending or loose links or rings K. 55

M represents a stationary plate, which is secured by screws or bolts m m to the connection or reach, and it is provided at its front 60 end with an upturned hook, M', which is adapted to be engaged by the rear end of the chain N, the front end of which is attached to the rear end of the sliding plate.

The advantage in providing the chain N, 65 which extends rearward from the bolster, is that the strain on the supporter is thus prevented from twisting or straining the bolster, and, further, the rear ends of the hounds are thereby prevented from bearing against 70 and wearing the under side of the coupling or reach. Further, by allowing the plate which is secured to the bolster a sliding movement forward and backward any sudden strain on the rear axle, caused by the rear 75 wheels running into a depression in the road, will not strain the chain N and the rear plate, M.

Having thus described my invention, I claim— 80

As an improved article of manufacture, the tongue-supporter comprising a plate, D, provided with downwardly-turned front and rear ends, and having a longitudinal slot, d, adapted to slide on the king-bolt of a vehicle, the 85 spring F, connected to the front end of the plate and having the loops G G' extending in opposite directions therethrough, the hooked plate L, adapted to be secured to the tongue, and the hooked plate M, adapted to be secured 90 to the reach or perch, the flexible chain I, attached to the end of the loop G' at the front end of the spring and provided at intervals with rings K, to engage the hooks on the plate L, and the chain N, attached to the rear end of 95 the plate D, and provided at its rear end with a ring engaging the hook on the plate M, all constructed and arranged substantially as specified.

In testimony that I claim the foregoing as 100 my own I have hereto affixed my signature in presence of two witnesses.

WILLIAM DAVIS NAPIER.
